CLAIM

The ornamental design for a bottle with integrated handle, as shown and described.

DESCRIPTION

FIG. 1 is a front perspective view of a bottle with integrated handle according to our new design;

FIG. 2 is a front elevational view;

FIG. 3 is a rear elevational view thereof;

FIG. 4 is a left side elevational thereof;

FIG. 5 is a right side elevational view thereof;

FIG. 6 is a top plan view thereof; and,

FIG. 7 is a bottom plan view thereof.

The broken lines shown are included for the purpose of illustrating the unclaimed portions of the bottle and form no part of the claim.
